(57) CLAIM

The ornamental design for a set of snaps and colored backings, as shown and described.

DESCRIPTION

FIG. 1 is a perspective view of a set of snaps and colored backings showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is an exploded perspective view of the upper portion of a set of snaps and colored backings showing my new design. The differently shaded backing of the set of snaps and colored backings indicate different color surfaces, but are not intended to indicate specific colors.
